UNITED STATES PATENT OFFICE

FRANCIS J. CONWAY, OF POTTSVILLE, PENNSYLVANIA

PROPELLER

Application filed June 15, 1928. Serial No. 285,661.

The present invention relates to a propeller and the objects and advantages thereof will appear as the description proceeds.

In the drawing:

5 Figure 1 is a front elevation of a propeller embodying the features of my invention,

Figure 2 is a sectional view therethrough taken substantially on the line 2—2 of Figure 1,

10 Figure 3 is a rear elevation thereof, and Figure 4 is a detail section substantially on the line 4—4 of Figure 1.

Referring to the drawing in detail it will be seen that the numeral 5 denotes a hub with a 15 plurality of blades 6 radiating outwardly therefrom and curved longitudinally only. The blades are straight transversely so that all transverse dimensions are parallel to the axis of the hub. The longitudinal curvatures 20 of the blades are all in the same direction reverse to the direction of rotation of the propeller indicated by the arrow 7.

On the ends of the blades 6 there is an 25 annular shroud 8. This shroud is curved transversely as is shown in Figure 2 so as to taper toward the front end of the propeller that is the end from which the air is coming. The shroud is wider than the blades and terminates rearwardly of the rear edges of 30 the blades.

In this propeller I depend upon the combined action of the set of blades and the inclined and curved shroud. I depend upon this set of blades building up a pressure on 35 the concaved inner surface of the shroud big enough for the desired lateral thrust.

This combination of shroud and blades is essential to the working of the device. 40 There are three distinct actions of the air when the propeller is being operated.

First, the air enters the front center of the propeller, through the opening in the shroud.

45 Second it comes into contact with the blades and changes its course from a direction parallel to the axis of the propeller to a direction at right angles to the said axis.

Third the air has both its velocity and 50 pressure increased by the action of the blades

as it comes into contact with the inclined and curved shroud.

The third action produces the desired lateral thrust by exerting a pressure against the concaved side of the inclined and curved shroud.

It is thought that the construction, utility and advantages of this invention will now be quite apparent to those skilled in this art without a more detailed description thereof.

The present embodiment of the invention has been disclosed in detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope 70 of the invention as hereinafter claimed or sacrificing any of its advantages.

Having thus described my invention, what I claim as new is:

A propeller comprising a hub, a plurality 75 of blades radiating from the hub and being curved longitudinally in an opposite direction to the direction of rotation of the propeller, said blades being substantially straight transversely, so that all transverse sections thereof are parallel with the axis of the hub, and a shroud of annular formation connecting the ends of these blades, said shroud being tapered toward one forward end of the propeller, and being curved transversely.

80 In testimony whereof I affix my signature.

FRANCIS J. CONWAY.
